No. 882,834.

PATENTED MAR. 24, 1908.

E. H. McCOLLOCH,
STOCKING.
APPLICATION FILED JULY 8, 1907.

UNITED STATES PATENT OFFICE

EUGENE H. McCOLLOCH, OF NEW ORLEANS, LOUISIANA.

STOCKING.

No. 882,834.

Specification of Letters Patent.

Patented March 24, 1908.

Application filed July 6, 1907. Serial No. 382,456.

To all whom it may concern:

Be it known that I, EUGENE H. McCOLLOCH, citizen of the United States, residing at New Orleans, in the parish of Orleans and 5 State of Louisiana, have invented new and useful Improvements in Stockings, of which the following is a specification.

My invention pertains to stockings of the kind that are equipped with means for the 10 attachment of stocking supporters; and it has for its object to provide a stocking of the class stated embodying such a construction that when a garment supporter is attached to the stocking the pull exerted by the supporter on the stocking is distributed around the stocking and in that way the use of the supporter in connection with the stocking is 15 prevented from tearing or otherwise deteriorating the stocking.

Another object of the invention is the provision of a stocking provided with such an equipment that the connection of a garment supporter to the stocking does not entail engagement of the supporter with any portion 20 of the textile material of the stocking.

Other objects and advantages of the invention will be fully understood from the following description and claims when the same are read in connection with the drawings accompanying and forming part of this specification, in which:

Figure 1 is a perspective view illustrating a stocking constituting the preferred embodiment of my invention as the same appears 35 when in position on the limb of a wearer and connected with a stocking supporter. Fig. 2 is an enlarged transverse section taken in the plane indicated by the line 2—2 of Fig. 1, looking in the direction indicated by the arrow. Fig. 3 is a view illustrating the arrangement of the reinforcing band and the depending reinforcing and strain-distributing strips of my improvements relative to the textile material of the stocking and precedent to the 40 connection of the said reinforcing band and strips to the said textile material. Fig. 4 is a view of a modified form of my invention in which the depending reinforcing strips are formed by welts woven into the textile or 45 other material of the stocking.

Referring by letter to the said drawings, and more particularly to Figs. 1, 2 and 3, thereof: A is a stocking which is shown as a ladies' stocking, and may be and preferably 50 is of the ordinary general construction. The textile material of the said stocking is turned

downward and inward at the top of the stocking and is sewed or otherwise attached to the inside of the major portion of the stocking, as best shown in Fig. 2, to form a hem B, and in the hem thus produced is arranged the reinforcing band or top strip C of my improvements. The said top reinforcing strip or band C is of canvas or other tough material and extends entirely around the top 60 of the stocking, and is secured in the hem B and to the material of the stocking, preferably by quilting the said hem B and the strip C as illustrated. When the hem B and the top strip C are quilted it will be apparent 65 that a strong connection of the strip C to the textile material of the stocking is effected, and at the same time the finished appearance 70 of the stocking as a whole is enhanced.

Permanently attached to or formed integral with the reinforcing band or strip C are three (more or less) depending reinforcing strips D of canvas or other strong material. These depending strips D are arranged equidistant and are permanently attached to the inner side of the stocking, preferably by 75 quilting the strips as illustrated, whereby it will be seen that when a stocking supporter is connected with the top strip or band C in the manner hereinafter described, the pull 80 exerted by the supporter will be distributed through a large portion of the textile material of the stocking, and hence the liability 85 of the said textile material being torn or stretched by the supporter is reduced to a minimum. When desired depending reinforcing strips D' formed by welts woven into the textile or other material of the stocking and attached at their upper end to the top strip or band C may be employed as 90 shown in Fig. 4 in lieu of the strips D, without involving departure from the scope of my invention as defined in the claims appended.

E are studs fixed in a permanent manner to the top reinforcing strip or band C and 100 extending forward through the major portion of the textile material of the stocking and having heads or enlargements at their forward ends, as best shown in Fig. 2. These studs E are for the detachable connection to 105 the stocking of the attaching members F of stocking supporting straps G, which attaching members F and straps G may be of the conventional construction or of any other construction compatible with the purpose of 110 my invention. At this point I desire to make it clear that in the discretion of the

manufacturer my novel stocking may be provided with one stud E or with a plurality of studs, though I prefer to employ a plurality of studs since when the same are provided 5 and the stocking is used in combination with a supporter having a single attaching member F, the said member F may be connected to the stocking at any desired point about the limb of the wearer. I would also have it 10 understood that the connection of the stocking to the stocking supporter through the medium of one of the studs E and an attaching member F does not entail engagement of the attaching member F with any portion of 15 the textile material of the stocking, and hence there is no liability whatever of the textile material being worn, torn or otherwise deteriorated by the action of the attaching member. From this it follows that my improvements are calculated to materially prolong the usefulness of the stocking as a whole, and this by the provision of means through 20 the medium of which a stocking supporter may be expeditiously and easily connected 25 to a stocking and as readily disconnected from a stocking.

It is obvious that in lieu of the studs E, the reinforcing strip or band at the top of the stocking may be provided with any other 30 appurtenances or appurtenance for the attachment of the stocking to a supporter, without involving departure from my claimed invention.

In addition to the practical advantages 35 hereinbefore ascribed to the stocking made in accordance with my invention, it will be noticed that the improved stocking is almost as cheap as an ordinary stocking and is quite as finished in appearance as the same.

40 The constructions herein shown and described constitute the preferred embodiments of my invention, but it is obvious that in practice such changes or modifications may

be made as fairly fall within the scope of my invention as defined in the claims appended. 45

Having described my invention, what I claim and desire to secure by Letters-Patent, is:

1. A stocking having its top portion turned downward and attached to its major portion 50 to form a hem, and a strip or band arranged in said hem, and reinforcing strips depending from said strip or band, and also having a device attached to the said strip or band and adapted for the engagement of the attaching member of a stocking supporter. 55

2. A stocking having its top portion turned downward and attached to its major portion to form a hem, and a strip or band arranged in said hem; said hem and strip or band being quilted, and reinforcing strips depending from the strip or band and attached to the major portion of the stocking, and also having a device attached to the said strip or band and adapted for the engagement of the attaching member of a stocking supporter. 60

3. A stocking having its top portion turned downward and attached to its major portion to form a hem, and a strip or band arranged in said hem; said hem and strip or band being quilted, and reinforcing strips depending from the strip or band at the inner side of the major portion of the stocking; said depending strips and major portion of the stocking being quilted, and a device attached to the 70 said strip or band and adapted for the engagement of the attaching member of a stocking supporter. 75

In testimony whereof I have hereunto set my hand in presence of two subscribing witnesses. 80

EUGENE H. McCOLLOCH.

Witnesses.
